UNITED STATES PATENT OFFICE.

AUGUSTE ROLLAND AND EDMOND LAMBERT CONINCK, OF PARIS, FRANCE.

ARGAND LAMP-BURNER.

SPECIFICATION forming part of Letters Patent No. 366,509, dated July 12, 1887.

Application filed September 18, 1886. Serial No. 213,884. (No model.) Patented in France December 18, 1884, No. 166,004; in Germany October 23, 1885; in England October 23, 1885, No. 12,737, and in Belgium October 24, 1885, No. 70,610.

To all whom it may concern:

Be it known that we, AUGUSTE ROLLAND and EDMOND LAMBERT CONINCK, citizens of the Republic of France, residing at Paris, in the said Republic, have invented certain new and useful Improvements in Argand or Circular Burners for Burning Petroleum and Other Liquids, of which the following is a specification, reference being had therein to the accompanying drawings.

Our invention relates to Argand or circular burners adapted for lamps in which petroleum or other oil is used; and the novelty consists, in general in the detail of construction relating to means for raising the wick and for preventing the oozing of the oil toward the outside, and of the chimney-carrier, and their combinations, all as will now be more fully described, as well as stated in the claims.

The accompanying drawings represent our invention in all its details.

Figure 1 is a vertical section drawn on the axis of the burner. Fig. 2 is a plan on line *y* *y*, Fig. 1. Fig. 3 is a side view of the wick-tube; Fig. 4, a vertical central section on a plane passing through the air-opening. Fig. 5 is an under side view of the external tube supporting the pinions and the chimney-holder, taken on line *y* *y*, Fig. 4. Fig. 6 is an under side view of the same tube, allowing a pinion to be seen in the place it occupies in the burner. Fig. 7 is an elevation of the pinion which adjusts the wick. Fig. 8 is a plan view of the ring carrying the grooves. Fig. 9 is a vertical central section, being the same view as in Fig. 1, enlarged.

The burner is furnished with the ordinary collar, *a*, for sealing, carrying at the interior a conical screw-ring, *b*, for the purpose above indicated, or simply a screw-ring, *c*, capable of being soldered to the body of the lamp. Above the collar is a base, *d*, soldered to the burner, which can be screwed on the collar or the body of the lamp. It carries inside a ring, *e*, with a flange or brim at its upper part to prevent the oozing of the petroleum.

On the bottom of revolving basket *f* is soldered the ring *g*, provided with helical-like grooves formed therein, and with the collar *h*, to retain at the lower part of the burner the petroleum which would ooze around the pin-

ions. This collar turns in the circular opening of ring *d*, thus serving as a pivot for the basket. The teeth of the pinions *i* engage in the grooves, so that they revolve when the basket *f* is turned. These pinions are held in position by a stamped-out piece, *l*, in form of a conical tube, and provided with the projection *m* perpendicular to its axis, and carrying three supports, *n*, (see Figs. 4, 5, and 6,) wherein the axles of the pinions are lodged. This tube is soldered to the burner by its lower part, and is concentric to the wick-tube *p*, the triangular opening *r* of which gives passage to the interior air-current. The excess of oil will find exit through the holes *x*, near the lower end.

The chimney-holder, which can be removed when required, is composed of a ring, *s*, made in one piece and bent in the form shown in Figs. 1 and 9. It has inside ribs *t*, which, projecting inward toward the tube *l*, serve to clamp the chimney in place. At the same time the spaces *u*, between the ribs *t*, allow a flow of air and for the oozing petroleum. The upper external and outer part, *v*, of this chimney-holder may be connected to the lower and inner part, *s*, in any ordinary way or manner.

With the burner constructed in the above manner, in raising the wick it is only necessary to turn the basket to the right; and to lower it, it is turned to the left.

Having now particularly described our said invention, and in what manner the same is to be constructed, we declare that what we claim is—

1. The combination, with an Argand lamp-burner, of the revolving basket *f*, having secured thereto the ring *g*, provided with helical grooves, with the pinion *i*, the conical tube *l*, and the wick-tube *p*, substantially as described.

2. The combination, with an Argand lamp-burner, of the conical tube *l*, and the projection *m*, the support *n*, the pinion *i*, the grooved ring *g*, and a basket, *f*, substantially as described.

3. The combination, with an Argand burner provided with the perforated wick-tube *p*, of the chimney-holder, having ribs *t*, the basket *f*, the grooved ring *g*, insulated from the wick-tube, and the wick-raising pinion supported as shown, substantially as and for the purposes described.

4. The combination, with an Argand lamp-burner, of the revolving basket *f*, and the grooved ring *g*, to which it is secured, the tube *l*, and pinion supported as shown, with the collar *h*, the screw-ring *d*, and the base *b*, in the manner and for the purposes set forth and described.

5. In an Argand burner, the wick-tube *p*, having triangular openings, and oil-exit holes to *x*, and the grooved ring *g*, supported thereby,

combined with the conical tube *l*, and the wick-raising mechanism constructed as shown, all substantially as described.

In testimony whereof we affix our signatures in presence of two witnesses.

AUG. ROLLAND.

EDMOND LAMBERT CONINCK.
